UNITED STATES PATENT OFFICE.

JAKOB FRIEDRICH MUNZ AND FRANK R. WELLS, OF SPRINGFIELD, OHIO.

GAS AND GASOLINE WATER-HEATER AND GRATE.

SPECIFICATION forming part of Letters Patent No. 351,335, dated October 19, 1886.

Application filed July 7, 1885. Renewed July 26, 1886. Serial No. 209,178. (No model.)

To all whom it may concern:

Be it known that we, JAKOB FRIEDRICH MUNZ and FRANK R. WELLS, citizens of the United States of America, residing at Springfield, in the county of Clark and State of Ohio, have invented certain new and useful Improvements in Gas and Gasoline Water-Heaters and Grates, of which the following is a specification, reference being had therein to the accompanying drawings.

This invention relates to an improvement in gas or gasoline grates and water-heaters combined; and it consists in the construction of the grate, including the water-heating attachment, substantially as hereinafter fully set forth and claimed.

In the accompanying drawings, Figure 1 is a plan view of our invention; and Fig. 2 is a sectional elevation of the same on the line x , Fig. 1.

In the said drawings, A refers to an annular reservoir or receptacle having a series of radial arms or bars, a , extending from its periphery, and which serve to support the annular receptacle or reservoir upon a gas or gasoline stove. Centrally of this reservoir, and connected to it by communicating hollow radial chambers B, is a ring, C, which serves to distribute the flame upon the various receptacles to fully utilize the flame and heat.

The radial chambers B are extended beyond the periphery of the annular chamber or receptacle A, to also form supports for the same, the whole contrivance thus constructed forming a combined grate and receptacle or vessel, the latter for heating water, which, it is obvious, promotes convenience, and facilitates the preparation of a meal as practiced in summer cooking.

Upon the upper surface of the annular chamber, intermediately of the radial chambers, are cast or formed bosses or upward projections e , upon which is designed to be supported, as well as upon the upper surfaces of the radial chambers, any other cooking or culinary utensil during the heating of the water or otherwise.

A suitable nozzle, b , is applied at one side of the reservoir A, through which the reservoir and its connecting-chambers may be filled with water, while the water after heating is drawn off through one or more nozzles, d , at other points of the reservoir.

Having thus fully described our invention, what we claim, and desire to secure by Letters Patent, is

1. In a combined grate and water-heater, the annular receptacle having the communicating radial chambers, said chambers being connected to a central ring and extended beyond the periphery of the said receptacle, substantially as and for the purpose set forth.

2. The combined grate and water-heater, comprising the annular chamber or reservoir, the central ring, the radial chambers between aforesaid chamber and ring, arms projecting beyond the annular chamber, and inlet and outlet nozzles, substantially as and for the purpose set forth.

In testimony whereof we affix our signatures in presence of two witnesses.

JAKOB FRIEDRICH MUNZ.
FRANK R. WELLS.
